UNITED STATES PATENT OFFICE.

GEORGE EDWARD MOORE, OF MUSKEGON, MICHIGAN, ASSIGNOR TO MANNING, MAXWELL & MOORE, INC., OF NEW YORK, N. Y., A CORPORATION OF NEW JERSEY.

TRAVELING CRANE.

Application filed February 11, 1924. Serial No. 691,955.

To all whom it may concern:

Be it known that I, GEORGE EDWARD MOORE, a citizen of the United States of America, residing at Muskegon, in the county of Muskegon and State of Michigan, have invented certain new and useful Improvements in Traveling Cranes; and I do hereby declare the following to be a full, clear, and exact description of the invention, such as will enable others skilled in the art to which it appertains to make and use the same.

This invention relates to a novel construction of traveling crane and one particularly designed for the purposes of safety in handling dangerous objects or materials. One place where the crane is of value is in the handling of molten metal as in transferring the same from a furnace to a mold. Cranes making use of cables and winding drums have been used but are not fully satisfactory. The cables, subjected as they are in service, to great strains become weakened by parting of strands thereof, many times within the cables. These breaks in the inner strands of the cables do not appear and the cables may become much weakened without any appearance thereof and finally part under load, allowing the load to drop with very disastrous results, especially when the load consists of many tons of molten metal carried in a container having an open top, with workmen underneath or under and to one side, death and serious injury almost always occurring in such cases.

My invention is directed to novel constructions in cranes whereby, as one feature of the invention, cables to take the strain of heavy loads of molten metal are wholly discarded, and a construction is used which is as nearly proof against giving way under load as can be devised. At the same time, the various movements of the load to carry it from one place to another, raising or lowering it, or moving it lengthwise or laterally with respect to the plane of the floor of the building in which the crane is installed, are provided for through novel mechanisms which constitute other valuable features of the invention. In addition there is coupled for use with the main load carrying devices of the crane, other independently operable hoisting mechanism which is of value in tipping or tilting the metal holding receptacle when its contents is to be poured into

molds, or for use in handling parts in making repairs to said main load carrying devices.

My invention consists in many novel features of construction and arrangements and combinations of parts for the successful attainment of the ends above outlined, together with many others not at this time specifically enumerated, but which will appear fully and in detail as understanding of the invention is had from the following description, taken in connection with the accompanying drawings, in which,

Fig. 1 is an elevation of the crane as mounted for operation in an open-hearth steel plant.

Fig. 2 is a somewhat enlarged transverse cross section through the crane bridge, showing the mechanism at one side of the plane of the section in elevation.

Fig. 3 is a vertical section taken substantially on the plane of line 3-3, of Fig. 2.

Fig. 4 is a horizontal section on the plane of line 4-4 of Fig. 2, with the covers for the gearing mechanisms removed to disclose the arrangement of the gearing.

Fig. 5 is a vertical transverse section through the vertically movable carrier mounted to traverse the depending supports which, in turn are carried by the trolley.

Fig. 6 is a fragmentary side elevation showing the trolley and the mounting of the depending supports thereon, and

Fig. 7 is a fragmentary side elevation of the lower end structure of said depending supports used to prevent disengagement of the vertically movable carrier therefrom.

Like reference characters refer to like parts in the different figures of the drawings.

In the mounting of the bridge of the crane, tracks 1 are used and secured in spaced apart relation, being suitably supported in any preferred manner in the building in which the crane is to be installed and located lengthwise thereof. The bridge includes two spaced apart sides 2 connected in any well known and conventional manner and carried on wheels 3 at their ends on the tracks 1. The wheels are driven through gears 4 fixed on the wheel shafts with which pinions 5 have engagement, said pinions being at the ends of a shaft 6 located lengthwise of the bridge and driven by a motor 7 through gearing

between the motor shaft and the shaft 6, gear 8 on the shaft 6 indicating the position of the gearing, as shown in Fig. 1. The usual cage 9 for the operator of the crane 5 is attached to move with the bridge. The operator has control of the motor 7 and by driving it in different directions may move the bridge back and forth on the tracks 1 to any desired position. The bridge, its mounting for movement, and the means for moving the same are all old in construction and need not be further specifically outlined.

The sides 2 of the bridge are comprised of built-up steel beams and are of great 15 strength and rigidity. On the upper side of each member 2, two parallel tracks 10 are mounted to carry a trolley designed to traverse the bridge lengthwise thereof. The trolley includes sides 11 having rollers or 20 wheels 12 and 12^a adjacent the ends thereof which run on the tracks 10. An electric motor 13 drives the shafts 15 on which the wheels 12^a are secured through suitable gearing which is housed in the housings 14. 25 Cross bars 16 and 17 connect the sides 11 of the trolley between which, at the upper side of each of the sides 11, trunnions 18 are formed integral with the sides of the carriage.

30 A built-up beam 19 is located over the trolley and between the bars 16 and 17, at each end and on its under side having a plate secured in which a trunnion socket or bearing 20 is formed so as to receive the trunnions 18, thereby mounting the beam for rocking movements. A depending supporting member 21 is connected with the beam 19 near each end thereof so as to pass downward at the inner side of each of the side 35 members 11 of the trolley. These members 21 are also of built-up steel construction and permanently secured at their upper ends to the beam 19 and braced so as to be rigid in connection therewith. At opposite sides 40 of each member 21, racks 22 and 23 are permanently secured, as shown.

45 A vertically movable carriage is mounted on the members 21 so as to traverse the same. In construction this vertically movable carriage has two side bars 24 of channel iron spaced apart, between which, at each end frames for carrying gearing are located and secured. Each frame comprises sides 24^a which lie alongside the end portions of the 50 channels 24, an end 25 and two spaced apart bars 26 and 27 parallel to each other and to the end 25, all formed as a single casting. The gearing referred to is mounted between the bars 26 and 27 and between the bars 55 25 and 26. In practice, I prefer to cover the mechanism between the bars 26 and 27 by suitable covers 28, and the gearing between the bars 25 and 26 by covers 28^a thereby preventing the entrance of dust or other 60 foreign matter.

Two electric motors 29 are mounted on suitable bracket feet 30 to the motor frames and supported on the I-beams 31 carried by and under the side channels 24. The motor shafts have pinions 32 fixed thereon which 65 mesh with gears 33, one on each of two shafts 34 located in parallel relation to each other and extending between the bars 27 and over the same to the adjacent bars 26, suitable bearings being provided in the bars 26 70 and 27 to rotatably mount the shafts. In addition, these shafts are supported at intermediate points by bearings formed at the ends of arms 30^a projecting from the motor frames 30. On the shafts 34 two gears 34^a 75 are fixed alongside of the bars 27, said gears being of the same size and meshing together. Two small gears 35 are also secured to the shafts adjacent the bars 26 serving to drive each of the four gears 36 which with pinions 37 80 are fixed on short shafts 38 located between the bars 26 and 27. The pinions 37 mesh with and drive gears 39 secured on shafts 40 extending from each inner bar 27 outwardly across the adjacent bars 26 and 25 to the ends 25, each of the shafts 40 also having a pinion 41 thereon adjacent the ends 25 which engage with and drive gears 42 on short shafts 43 on which are also wide pinions 44 in engagement with the racks 95 22 and 23. It is apparent that the four pinions 44 serve to move along the tracks made by the racks 22 and 23 and raise or lower the vertically movable carriage, the shafts 34 running in opposite directions and 100 in unison so as to equalize the movement of the carriage on the supporting members 21 at all times. The control of the motors 29 is exercised by the operator of the crane from his stage of operation. The coupling 105 of the shafts 34 together by the gears 34^a permits the working of the carriage under light loads by one motor, if desired, and the coupling of the two motors together to add their powers when both are operating. A 110 brake band 45 around a suitable drum on each shaft 34 is actuated by an arm 46 to tighten against the drum or loosen therefrom, the operation of the brakes being identical with the operation of the same on elevators; that is, the brakes are normally set by springs when the mechanism is at rest 115 and released by solenoid operation as the current passes to the motor to start the same. This acts to cause an automatic setting of 120 the brakes when the power is cut off. The solenoid position is diagrammatically indicated at 47 but the detail of construction is not illustrated, the same being old and well known.

125 From the ends 25 and cross bars 26 and 27 of the frame in which the gearing just described is mounted, plates 48 extend downwardly for a short distance, at the lower 130 ends of which bars of I-beam cross section,

as indicated at 49 are secured, lying one at each side of the supporting members 21 and closely adjacent to the racks 22 and 23 thereon. The plates 48 depending from the cross bars 26 are extended below the plane of the bars 49 and other plates 50 are connected to and depend from said bars in parallel relation thereto so that pivot pins 51 may be interposed between on which hook members 52 are pivotally mounted. These hook members, preferably are made from several laminations of steel plate and have hooks formed at their lower ends for the reception of trunnions 53 projecting in opposite directions 15 from a frame 54 in which a ladle 55 adapted to receive molten metal is carried.

At the lower ends of the outer plates 48 bars 56 of angle iron are permanently secured in horizontal position which, in the 20 lowermost position of the vertically movable carriage on the members 21 and as the pinions 44 are about to leave the racks 22 and 23 come against bumper blocks 57, spring supported by springs 58 which are supported on and above fixed bars 59 at the 25 lower ends of the members 21. This is one means of insuring that the carriage with its load of ladle with or without its molten metal contents shall not detach from and 30 drop off the members 21. Any other equivalent stop means may be used, as may be designed for the purpose.

From the foregoing, it will be evident that the ladle may be moved with the bridge 35 lengthwise of the building in which the crane is installed, may be moved with the trolley on the bridge back and forth to different positions between the ends of the bridge, and may be raised and lowered to 40 any position within the limits imposed by the racks 22 and 23 and the pinions 44 engaging therewith. For instance, as shown in Fig. 1, the ladle may be carried over to and lowered under the outlet spout 60 to a 45 furnace, the ladle being filled with molten metal and then carried to ingot molds 61 mounted on cars 62 which traverse tracks 63. The ladle is tapped at the bottom to deliver 50 its contents into the molds and the molds may be moved along in succession to receive the metal from the ladle.

In order to tip or tilt the ladle, I have mounted a second trolley with hoisting apparatus thereon on members 64 having 55 tracks 65 at their upper sides on which the trolley is mounted. The members or beams 64 are located between the sides 2 of the bridge and parallel thereto, being secured at their ends so as to rigidly connect with and move with the bridge. The second trolley includes sides 66 connected together and having wheels 67 to ride on the tracks 65, the sides being connected by cross members 68 above which a winding drum 69 is mounted and on which cables 70 are

adapted to be wound. A fixed pulley block 71 is secured to the trolley and a movable pulley block 72 located under the trolley with the cables threaded therethrough, a hook 73 depending from the block 72 which 70 may be used to connect with the loop 74 on the bottom of the ladle 55, it being evident that with the winding of the drum 69 to take in the cables, the block and attached hook 73 are raised and the ladle may be 75 tilted thereby. The trolley is movable along the tracks 65 and the drum is operated by an electric motor, indicated at 75. The specific mechanisms by which these operations are accomplished do not enter 80 into the present invention, and are not described and shown herein. The second hoisting mechanism, in addition to its use as a means for tilting the ladle, may be used for many other purposes, in fact for any 85 of the purposes for which a relatively small hoisting apparatus movably mounted on a crane bridge may be used, and in the particular combination shown it is of value in handling parts and the like in making repairs on the main ladle handling apparatus. 90

The structure described is particularly adapted for the safe handling of heavy materials wherein all danger of breakage or other failure of the construction to operate must be avoided. There are no cables on which the weight of the molten metal must bear and by which it must be sustained. The strong and rigid members 21 carrying the load are amply strong to sustain the 100 same, and any likely breakage therein is readily detected and remedied before it occurs. The swinging mount of the beam 19 permits a latitude of movement of the load which is advantageous at times and relieves strains on the construction. All parts are 105 easily inspected and may be kept in repair and to full strength at all times.

The appended claims define the invention, and it is to be considered that all forms of 110 structure coming within the scope of said claims are comprehended by this invention.

I claim:

1. A crane comprising a bridge, a trolley mounted to traverse the bridge in a direction at right angles to the movement of the bridge, spaced apart depending supporting members depending from the trolley between the ends thereof, a vertically movable carriage mounted on and extending horizontally 115 between said members for vertical movements, and means for moving said vertically movable carriage up and down on said members, substantially as and for the purposes described. 120

2. A crane comprising a bridge movably mounted to travel horizontally in one direction, a trolley mounted on the bridge for movement horizontally in a direction at right angles to the direction of movement of 130

the bridge, two spaced apart vertical members carried by and movable with the trolley and extending downwardly below the bridge between the ends of said trolley, a carriage mounted on and extending horizontally between said members for vertical movements and means for actuating said carriage to move it up or down on said members.

3. A crane comprising a bridge movably mounted to travel horizontally in one direction, a trolley mounted on the bridge for movement horizontally in a direction at right angles to the direction of movement of the bridge, two spaced apart vertical members carried by and movable with the trolley and extending downwardly between the ends of said trolley below the bridge, racks on opposite sides of said members, a carriage located between and around said members, gearing mounted on the carriage and engaging the racks, and means for driving the gearing in either direction to raise or lower the carriage on the said members, substantially as described.

25 4. A crane comprising a bridge movably mounted to travel horizontally back and forth in one direction, a trolley mounted on the bridge to move horizontally back and forth in a direction at right angles to the direction of movement of the bridge, a beam mounted for rocking movements on the trolley longitudinally of the bridge, two members depending from the beam in spaced apart relation, and a load carrying carriage mounted on said members for up and down movements thereon, substantially as described.

5. A crane comprising a bridge movably mounted to travel horizontally back and forth in one direction, a trolley mounted on the bridge to move horizontally back and forth in a direction at right angles to the direction of movement of the bridge, a beam extending between the ends of the trolley and mounted on said ends of the trolley to swing about a horizontal axis parallel to the length of the beam, two members rigidly connected to and depending from the beam inside of the ends of the trolley, and a load carrying carriage mounted on said members for movements up and down thereon, substantially as described.

6. In a crane, a movably mounted trolley, a beam mounted for rocking movements about a horizontal axis and mounted on the trolley, two rigid members rigidly connected to said beam at their upper ends and extending downwardly from said beam, a load carrying carriage mounted on said members to traverse the same, and means for actuating said load carrying carriage to move the same in either direction on said members.

7. In a crane, a movably mounted trolley, a beam mounted horizontally on and above said trolley, rigid members connected at

their upper ends to and depending from the beam one inside each end of the trolley, a load carrying carriage mounted on the members to traverse the same, and means for actuating the load carrying carriage to move the same in either direction on said members.

8. In a crane, a trolley mounted for movements back and forth in a horizontal plane, two spaced apart rigid members carried by the trolley and depending below the same, means for mounting said members on the trolley whereby the same may swing in unison about a horizontal axis, racks on opposed sides of the members, a load carrying carriage located between and around said members, pinions on the carriage engaging the racks, and means for driving the pinions in unison to cause the load carrying carriage to traverse said members.

9. In a crane, a movably mounted trolley adapted to move back and forth in a horizontal plane, a beam mounted horizontally for rocking movements about a horizontal axis on the trolley, two spaced apart rigid members fixed at their upper ends to the beam and depending below the same, racks on opposite sides of the members, a load carrying carriage, pinions on the load carrying carriage meshing with the racks, and means to drive the pinions to cause the load carrying carriage to traverse said members.

10. In a crane, a trolley mounted for movements back and forth in a horizontal plane and including two spaced apart connected sides, each being formed with a trunnion, a beam located above the trolley, socket members attached to the beam at its ends and engaging with said trunnions whereby the beam may have a rocking movement, depending rigid members rigidly attached at their upper ends to said beam, and a load carrying carriage mounted on and adapted to traverse said members.

11. In a crane, a trolley mounted for movements back and forth in a horizontal plane, two spaced apart rigid members carried by the trolley and extending downwardly therefrom, each of said members having a rack on each of two opposed sides thereof, a carriage mounted on said members, pinions on the carriage engaging the racks, an electric motor carried by the carriage, and gearing connections between the motor and said pinions for driving the pinions from the motor, substantially as and for the purposes described.

12. In a crane, a trolley mounted for movements back and forth in a horizontal plane, two spaced apart rigid members carried by the trolley and extending downwardly therefrom, racks on opposed sides of each of the members, a load carrying carriage mounted on said members, pinions on the carriage in mesh with the racks, two electric motors on the carriage, and gear-

ing connections between the motors and the pinions whereby all of the pinions may be driven by either of the motors or by the motors working together.

- 5 13. In a crane, a trolley mounted for movements back and forth in a horizontal plane, two spaced apart rigid members carried by the trolley and extending downwardly therefrom, racks on opposed sides 40
10 of each of the members, a load carrying carriage mounted on said members, pinions on the carriage in mesh with the racks, two shafts mounted on the carriage in parallel relation to each other, a motor for driving each shaft, gearing connections between the shafts for causing the same to turn equally in unison, and gearing connections between each end of each shaft and one of the pinions, substantially as described.
- 15 14. In a crane, a trolley mounted for movements back and forth in a horizontal plane, two spaced apart rigid members carried by the trolley and extending downwardly therefrom, a carriage mounted on 45
20 the members for movements up and down thereon, said carriage including an upper frame of rectangular outline, means carried on said frame for actuating the carriage for movement along said members, members 50
25 depending from the frame, bars attached to said members below the frame, and hooks pivotally connected to the members and depending therefrom, substantially as and for 55
30 the purposes described.
- 30 15. In a crane, a horizontally movable trolley, a beam located transversely thereof and having a rocking mount on the trolley, members rigidly attached to the beam and extending downwardly therefrom, a load 60
35

carrying carriage mounted on the members 40
40 for vertical movements upwardly and downwardly thereon, means for actuating the carriage to move the same in either direction along said members, and two spaced apart hooks pivotally connected to and depending from the carriage, substantially as 45
45 described.

16. In a crane, a bridge, a trolley mounted on the bridge for back and forth movements lengthwise of the bridge, a beam mounted transversely of the trolley for rocking movements about an axis parallel to the center line of the beam, two rigid members rigidly attached at their upper ends to the beam at spaced apart points and depending 50
50 from the beam, a rack on each of two opposed sides of each of the members, a load carrying carriage mounted to traverse the members, pinions on the carriage engaging with the racks, two motors mounted on the carriage, two shafts driven by the motors, gearing between the shafts for causing the shafts to be driven equally and in opposite directions, and gearing between each end of each shaft and a pinion, substantially as 55
60
65 and for the purposes described.

17. In a crane, a trolley, means for mounting the same, two rigid members depending below and carried by the trolley, said members each carrying two racks on opposed 70
70 sides of the members, a load carrying carriage mounted to traverse the members, pinions on said load carrying carriage engaging the racks, and means on the carriage to drive the pinions.

In testimony whereof I affix my signature.

GEORGE EDWARD MOORE.
